WET REFUSE BURNING BOILER AND
FURNACE INSTALLATION

Louis J. Schrenk, Detroit, Mich., assignor to Combustion Engineering Company, Inc., New York, N. Y., a corporation of Delaware

Application April 9, 1934, Serial No. 719,637

14 Claims. (Cl. 122—2)

This invention relates to boiler and furnace installations adapted for use in burning wet refuse, such as garbage, sewage screenings or the like, and also for burning mixtures of wet fuel and relatively drier fuel, for the purpose of generating steam.

I propose to burn other fuel in space in the installation, such as pulverized coal, in conjunction with the wet fuel or refuse, in order to bring about combustion of the latter. This other fuel is directed toward the wet refuse in the furnace so that the heat of its flame dries and ignites the wet refuse.

It is an object of my invention to provide a novel hearth or grate arrangement in a pulverized fuel burning boiler and furnace installation for the effective burning of wet refuse and the like in conjunction with the pulverized fuel, or for the burning of the latter alone when desired.

Another object resides in associating the hearth or grate with an inclined water screen located in the lower portion of the furnace.

A further object resides in admitting air into the furnace in a manner to obtain effective combustion of both fuels being burned.

It is also an object of my invention to provide an arrangement whereby existing pulverized fuel burning installations may be readily converted into installations especially adapted for the burning of wet refuse.

Another object is the provision of an arrangement whereby wet refuse may be effectively burned for the generation of steam at high capacity.

Other objects have to do with features of control which will be set forth hereinafter as they will be more readily understood in connection with the description of the invention.

How the foregoing together with such other objects and advantages as may hereinafter appear or are incident to my invention are realized, is illustrated in preferred form in the accompanying drawings, wherein—

Fig. 1 is a sectional elevation through a boiler and furnace installation embodying my invention.

Fig. 2 is an enlarged fragmentary plan view, illustrating a hearth or grate detail.

Fig. 3 is an enlarged side view of the hearth; and

Fig. 4 is a cross section on the line 4—4 of Fig. 3.

The installation illustrated in Fig. 1 comprises in general, a boiler A, in this instance of the horizontally inclined tube type, having an upper steam and water drum 4, front downcomer head-

ers 5, rear upcomer headers 6, inclined boiler tubes 7 connecting the headers, and suitable connections between the headers and drum; a furnace B located below the boiler having upright steam evaporating tubes 8 at upright walls thereof; a water screen C in the lower portion of the furnace; and burner means D for introducing fuel, such as pulverized coal, into the combustion chamber of the furnace to be burned in space therein. A superheater E may be provided in the rear wall of the furnace.

The furnace illustrated is of the dutch oven type in which the burner means D are located to deliver fuel to be burned in space downwardly through the arch of the dutch oven F and adjacent the front wall thereof. A draft outlet G is provided in the upper part of the installation for drawing the gaseous products of combustion over the tubes of the boiler and the fuel is burned in a U-shaped flame, as diagrammatically indicated in Fig. 1.

The radiant heat steam evaporating tubes 8 are connected to receive water from and deliver steam to the boiler by means of lower and upper headers 9 and 10 and suitable downcomers 11 and upcomers 12.

The water screen C comprises a plurality of tubes 13 spaced apart crosswise of the furnace, as illustrated in Figs. 2 and 4 and inclining upwardly from the front to the rear of the furnace. The tubes are connected at their lower ends into a downcomer header 14 and at their upper ends into an upcomer header 15, water being supplied to the downcomer header by means of downcomer tubes 16 leading from the water space of the steam and water drum 4 and delivery from the water screen being to the steam space of the drum 4 by means of upcomer tubes 17.

The hearth or grate for the burning of the wet refuse is associated with the water screen and comprises a plurality of rows of tiles or blocks 18, preferably made of cast iron, arranged to have air spaces 19 therebetween as illustrated in Fig. 3. The tiles are socketed along their side edges as indicated at 20 in Fig. 4 so as to rest on the tubes 13 of the water screen, and have their top surfaces 21 inclined, as shown in Fig. 3. The tiles 18 are secured to the tubes 13 by means of clamping devices 22 in spaced relation so as to provide the air spaces 19 between adjacent tiles, and the front edges thereof are provided with projecting portions 23 which overhang the rear edges of the adjacent tiles to prevent the fuel being burned on the grate from falling through the spaces. In addition to the air spaces 19, I also contemplate

providing side air openings 24 which lead to the longitudinal spaces 25 between adjacent tiles crosswise of the grate. At the lower end of the grate, I provide special tiles 26 which are clamped 5 to the tubes in a manner similar to the clamping of the tiles 18 and serve as supports for the remaining tiles. At the upper end of the grate 10 filler members 27 are provided to close the gap between the uppermost tiles and the rear wall of the furnace.

The grate extends from the rear wall of the furnace downwardly along the tubes to a point short of the front furnace wall so as to provide a space at 28 for the discharge of ash from the 15 lower end of the hearth, it being noted that the spacing of the tubes is such as to freely permit of such discharge between the tubes. The exposed portions of the screen tubes at this point 20 serve to prevent slagging difficulties from the burning of the pulverized coal.

The wet refuse to be burned is fed into the furnace at the upper end of the hearth by means of feeding mechanism H, in this instance comprising a plurality of rams or pushers 29 so spaced 25 crosswise of the furnace as to provide a bed of refuse covering the entire width of the hearth. The rams are reciprocated by any suitable form of reciprocating mechanism 30, such as compressed air or steam operated cylinder and piston 30 mechanisms.

The feeding mechanism is of a type in which the rams may be individually operated, or in unison, as desired and in which the length of stroke of the rams may be adjusted, whereby uniform 35 flow of the refuse may be maintained under different operating conditions. Suitable hoppers 31 are provided for feeding the refuse to the rams, and the rams feed the refuse into the furnace through the medium of discharge throats 32. In 40 order to prevent arching or packing of the refuse in the hoppers and discharge throats, these are constructed to flare outwardly in the direction of flow of the refuse.

Air is supplied to the bed of burning refuse by 45 means of a plurality of air compartments 33 located under the hearth, and in this instance, I have shown four such compartments. Air under pressure, preferably preheated, is supplied to the compartments 33 by means of a conduit 34 50 having four branches 35, one for each compartment 33, each of which is provided with a damper 36 for controlling the flow of air. The control of air to the various parts of the wet fuel bed compensates for different rates of combustion and/or 55 fuel bed resistance, due to distribution of the wet fuel.

Movement of the rams 29, combined with the downward slope of the hearth or grate and the method of supplying air therethrough, causes the 60 bed of burning refuse to move over the entire length of the hearth, it being pointed out that the movement of the rams and supply of the air is so timed that when the refuse reaches the lower end of the hearth, practically all combustibles 65 have been burned out. The ash drops off the lower end of the hearth and is mostly in finely divided form so that no difficulty from fusion of ash is encountered.

The pulverized coal burners B above referred to, 70 admit pulverized coal mixed with primary air into the combustion chamber in a direction toward the bed of refuse and the burning mixture travels vertically downward toward the hearth and then takes a U turn and flows upwardly 75 through the outlet of the furnace. The propor-

tions of the installation are preferably such that the burning mixture makes the U shape turn at approximately two feet above the lower end of the hearth. Thus the lower nearly horizontal part of the U turn passes closely over the bed of refuse.

Secondary air is supplied through controlled ports 37 in the hollow front wall of the furnace for the purpose of completing combustion of the fuel so admitted. A conduit 37a may lead 10 preheated air to the hollow front wall as illustrated in Figure 1. The lower portion of the fuel and flame stream sweeps over the bed of refuse in a direction opposite the movement of the bed of refuse over the hearth, and the high 15 temperature of the flame supplies heat for drying and igniting the refuse.

I contemplate supplying air through the hearth and the bed of refuse thereon somewhat 20 in excess of that needed for complete combustion of the refuse which aids in completing the combustion of the pulverized coal introduced by the burners D. Control of combustion may be accomplished by adjusting the amount of air admitted through the hearth to the amount of 25 secondary air admitted through the front wall of the furnace. Stated more specifically, in burning the combined fuels with excess air through the bed of fuel on the hearth a compensating deficiency of air is supplied to the pulverized fuel 30 stream.

Complete combustion of any volatile products of the refuse is insured because of the high temperature in the combustion chamber above the bed of refuse so that in the case of burning garbage, objectionable odors in the stack gases 35 are reduced.

It is also pointed out that if it is desired at times to burn pulverized coal alone, wet refuse may be fed onto the hearth to cover it, after 40 which the feed is stopped and the air supply through the hearth shut off. Thus, combustion of the refuse on the hearth practically ceases and the refuse remains there to protect the hearth from the intense heat of the coal flame. 45 Although the length of time during which pulverized coal may be burned alone is limited by the accumulation of coal ash over the bed of refuse, such burning nevertheless can continue for periods of many hours and until the accumulation of the coal dust ash is sufficiently deep 50 to bring about slagging of the surface thereof. Before this occurs, the ash on the hearth must be discharged and a new wet fuel bed provided.

When the installation is employed for the 55 burning of garbage or the like, the garbage is partly dehydrated as by means of roller presses, in order to reduce the moisture therein, and this for the reason that the lower the moisture content, the higher the efficiency with which the 60 garbage can be burned in the installation.

In the case of burning rubbish in which the combustible part consists of paper, wood, cloth, leather and similar materials, the moisture content is much lower than that of garbage and 65 therefore it can be burned much more readily and makes a better steaming fuel. The rubbish may be reduced to uniform size as by means of a lacerating machine so that it can be handled by the conveying and furnace feeding equipment. 70 Instead of dehydrating the green fuel, it may be mixed with rubbish so as to bring down the proportion of moisture.

I claim:

1. A combined pulverized fuel and wet refuse 75

- burning boiler and furnace installation comprising, a boiler, a combustion chamber, an inclined water screen in the lower portion of and extending across the combustion chamber, means connecting said water screen into the boiler circulation, a perforate hearth carried by and terminating short of the lower portion of the water screen, means for introducing pulverized fuel and air into the combustion chamber directed toward the hearth, means for admitting secondary air into the combustion chamber, means for feeding wet refuse onto the hearth, and means for supplying air through the hearth and the bed of refuse thereon.
15. A combined pulverized fuel and wet refuse burning boiler and furnace installation comprising a boiler, a combustion chamber, an inclined water screen in the lower portion of and extending across the combustion chamber, means connecting said water screen into the boiler circulation, a perforate hearth carried by and terminating short of the lower portion of the water screen, means for introducing pulverized fuel and air into the combustion chamber directed toward the hearth, means for admitting secondary air into the combustion chamber, means for feeding wet refuse onto the hearth, and means for supplying pressure air through the hearth and the bed of refuse thereon comprising a plurality of air chambers below the hearth and means for individually controlling said chambers.
30. 3. A combined pulverized fuel and wet refuse burning boiler and furnace installation comprising a boiler, a combustion chamber, an inclined water screen in the lower portion of and extending across the combustion chamber, means connecting said water screen into the boiler circulation, a perforate hearth carried by and terminating short of the lower portion of the water screen, means for introducing pulverized fuel with primary air into the combustion chamber directed toward the hearth, means for controllably admitting secondary air into the combustion chamber, means for feeding wet refuse onto the hearth, and means for controllably supplying air through the hearth and the bed of refuse thereon.
45. 4. A combined pulverized fuel and wet refuse burning boiler and furnace installation comprising a boiler, a combustion chamber, a water screen in the lower portion of the combustion chamber comprising a row of spaced water tubes extending across the combustion chamber and inclining upwardly from front to rear thereof, means connecting said water tubes into the boiler circulation, a perforate hearth carried by said water screen and ending short of the lower portion thereof to provide for ash discharge at said lower portion, means for introducing pulverized fuel into the combustion chamber in a direction toward the hearth, means for feeding wet refuse onto the hearth, and means for introducing air under pressure through the hearth and bed of refuse thereon.
60. 5. A combined pulverized fuel and wet refuse burning boiler and furnace installation comprising a boiler, a combustion chamber, a water screen in the lower portion of the combustion chamber comprising a row of spaced water tubes extending across the combustion chamber and inclining upwardly from front to rear thereof, means connecting said tubes to be supplied from and to deliver into the boiler, a grate comprising tiles supported on said tubes and provided with air spaces therebetween for the admission of air from below, said grate terminating short of the
- lower portion of the water screen to provide for the discharge of ashes to an ashpit below, means for feeding wet refuse onto the grate, and means for introducing pulverized fuel into the combustion chamber in a direction toward the grate. 5
6. A combined pulverized fuel and wet refuse burning boiler and furnace installation comprising a boiler, a combustion chamber, an inclined water screen in the lower portion of the combustion chamber comprising a row of spaced water tubes extending across the combustion chamber and inclining upwardly from front to rear thereof, a grate comprising tiles supported on the tubes of the water screen, said tiles having means supporting them to provide air spaces between them, means for feeding wet refuse onto the grate, means for introducing pulverized fuel into the combustion chamber in a direction toward the grate, and means for passing air through the grate and bed of refuse from below. 10
20. 7. A combined pulverized fuel and wet refuse burning boiler and furnace installation comprising a boiler, a combustion chamber, an inclined water screen connected into the boiler circulation extending across the lower portion of the combustion chamber, a grate comprising tiles supported on the water screen in spaced relation to provide air spaces therebetween, means on the tiles overhanging said spaces, means for feeding wet refuse onto the grate, means for introducing pulverized fuel into the combustion chamber in a direction toward the grate, and means for passing air through the grate and bed of refuse from below. 25
30. 8. A combined pulverized fuel and wet refuse burning boiler and furnace installation comprising a boiler, a dutch oven combustion chamber therebelow, burner means adapted to deliver fuel to be burned in space downwardly through the arch of said dutch oven and adjacent the front wall of the combustion chamber, a hearth in the lower portion of the combustion chamber inclining downwardly from the rear wall of the chamber and adapted to receive wet refuse, means for feeding the refuse onto said hearth at the upper end thereof, means for admitting air through the hearth and bed of refuse thereon, and a draft outlet in the upper part of the installation for drawing the gaseous products of combustion over the tubes of the boiler, the distance between the arch and the hearth being such that the fuel admitted by the burner means is burned in a U-shaped flame with the bottom of the flame passing over the bed of refuse in close but spaced relation thereto. 35
45. 9. A combined pulverized fuel and wet refuse burning boiler and furnace installation comprising a boiler, a combustion chamber directly therebelow, an inclined hearth in the lower portion of said chamber, means for feeding wet refuse onto the hearth at the upper end thereof, a dutch oven extension at the front of said chamber, said hearth being inclined downwardly from the rear of the combustion chamber and terminating in the dutch oven extension to provide an ash discharge space adjacent the front of the extension, burner means for introducing fuel downwardly in the dutch oven to be burned in space therein and in the combustion chamber proper with exit for the product of combustion from the upper 50
55. part of the combustion chamber whereby a flame bending upwardly over the refuse bed is produced. 60
70. 10. A combined pulverized fuel and wet refuse burning boiler and furnace installation comprising a boiler, a combustion chamber directly there- 75

below, radiant heat steam evaporating tubes at walls of said combustion chamber, an inclined hearth in the lower portion of said chamber, means for feeding wet refuse onto the hearth at the upper end thereof, a dutch oven extension at the front of said chamber, said hearth being inclined downwardly from the rear of the combustion chamber and terminating in the dutch oven extension to provide an ash discharge space adjacent the front of the extension, burner means for introducing fuel downwardly in the dutch oven to be burned in space therein and in the combustion chamber proper with exit for the product of combustion from the upper part of the combustion chamber whereby a flame bending upwardly over the refuse bed is produced.

11. A combined pulverized fuel and wet refuse burning boiler and furnace installation comprising a boiler, a combustion chamber therebelow, a hearth extending across the bottom of the combustion chamber and inclining downwardly from the rear wall of the chamber and adapted to receive wet refuse, means for feeding the refuse onto said hearth at the upper end thereof, burner means adapted to deliver fuel to be burned in space adjacent the front wall of the combustion chamber, said hearth terminating short of the front wall of the combustion chamber to provide for the discharge of ashes to an ashpit below, and means for supplying air through the hearth and the bed of refuse thereon.

12. A combined pulverized fuel and wet refuse burning boiler and furnace installation comprising a boiler, a combustion chamber, a water screen in the lower portion of the combustion chamber comprising a row of spaced water tubes extending across the combustion chamber and inclining upwardly from front to rear thereof, means connecting said tubes to be supplied from and to deliver into the boiler, a grate comprising tiles supported on said tubes and provided with air spaces

therebetween for the admission of air from below, said grate terminating short of the lower portion of the water screen to provide for the discharge of ashes to an ashpit below, means for feeding wet refuse onto the grate, and means for introducing pulverized fuel and primary air for combustion thereof into the combustion chamber in a direction toward the grate.

13. A combined pulverized fuel and wet refuse burning boiler and furnace installation comprising a boiler, a combustion chamber, a water screen in the lower portion of the combustion chamber comprising a row of spaced water tubes extending across the combustion chamber and inclining upwardly from front to rear thereof, means connecting said tubes to be supplied from and to deliver into the boiler, a grate comprising tiles supported on said tubes and provided with air spaces therebetween for the admission of air from below, said grate terminating short of the lower portion of the water screen to provide for the discharge of ashes to an ashpit below, means for feeding wet refuse onto the grate, and means for introducing pulverized fuel and primary air for combustion thereof into the combustion chamber in a direction toward the grate, together with means for introducing air through the hearth and bed of refuse thereon.

14. The method of burning wet refuse which consists in advancing said refuse over a hearth while subjecting its upper surface to the radiant heat of the flame of a fuel introduced with primary air in controllable deficient quantities for complete combustion thereof in a direction toward said surface and controllably supplying air through the hearth and the bed of refuse thereon in excess to that needed for complete combustion of said refuse, said excess supplying said deficiency for the complete combustion of said fuel.

LOUIS J. SCHRENK.
